UNITED STATES PATENT OFFICE

RICHARD M. HEAMES, OF GROSSE POINTE, MICHIGAN

METHOD OF FORMING BLANKS

No Drawing.

Application filed February 1, 1928. Serial No. 251,229.

The present invention relates generally to improvements in the art of manufacturing certain types of metallic objects, and relates more specifically to a new and useful method 5 of forming metal blanks directly from relatively unfinished material such as rod stock.

An object of the invention is to provide an improved process of forming cap screw blanks or the like, directly from relatively 10 crude rod stock, thereby materially reducing the cost of production by eliminating necessity of utilizing the more expensive drawn wire stock previously employed for such purposes. Another object of the invention is to 15 provide an improved method of manufacturing cap screw or similar blanks, whereby successive blanks of accurate predetermined dimensions and of uniform and substantially identical structure may be produced. A further object of the invention is to provide a 20 method of producing headed blanks, whereby the flow of metal during formation of the heads and shanks is maintained symmetrical with respect to the blank axes, and wherein no 25 portion of the metal is overstressed.

The term "rod stock" as used herein, is intended to designate rod-like cylindrical bars of variable length produced in the steel mills by merely rolling heated billets into rods of 30 an approximate diameter, these rods being subsequently pickled or otherwise treated to remove the scale. This rod stock is obtainable at relatively low cost and is also comparatively soft and hence readily workable, thus 35 making its use in large quantities rather economical. The term "wire stock" as used herein, is intended to designate the product resulting from drawing rod stock while cold, through a die to accurate and uniform diameter. The stock thus produced is appreciably 40 "work hardened" during the cold drawing operation, and the finished wire stock is also more expensive due to the cost of drawing, than the original rod stock.

45 It has heretofore been universal commercial practice in the cold heading industry, to utilize drawn wire stock in the formation of cap screw, bolt, and other types of headed blanks. During the formation of such blanks 50 from drawn wire stock, the wire is severed

into pieces of proper length, each of which is subsequently deformed by means of suitable punches and dies, to provide an enlargement or head at one end and a shank at the opposite end. The heads of the blanks are 55 produced by upsetting the ends of the severed pieces, thus providing enlargements which are far greater in transverse cross-section, than the original rod stock from which the wire stock has been drawn. When the blanks are of the type wherein a portion of the shank is of reduced diameter in order to permit subsequent application of rolled threads, the wire stock utilized in their formation may have a diameter, either substantially equal to that of the smallest final shank 60 diameter, or substantially equal to that of the larger final shank diameter. When utilizing wire stock which is substantially equal in diameter to that of the smallest shank diameter, it is also necessary in the formation of 65 the blanks, to upset the shank portion of each blank which is to have the greatest final diameter, at least up to or beyond the diameter of the original rod stock from which the wire 70 has been drawn. When utilizing wire stock which is substantially equal in diameter to that of the larger shank diameter, it is necessary in the formation of the blanks, to draw down the portion of each blank to which the 75 rolled thread is to be subsequently applied. It will be apparent that irrespective of the diameter of the wire stock employed in the production of the blanks in accordance with the prior methods, the work done in enlarging 80 the wire stock to the original rod stock diameter when forming the head and when enlarging a shank portion, is wasted effort and undesirably stresses and hardens the metal. The use of wire stock in the formation 85 of the blanks in cases where a portion of the wire stock remains undeformed in the final blank, also requires the provision of relatively accurately predetermined tolerances in order to enable the wire stock to be 90 passed freely through the openings of the punches or dies without excessive clearance.

With the foregoing objections to the prior method of forming blanks in mind, it is the purpose of the present invention to provide 100

a method wherein the blanks may be formed directly from the rod stock and before the same is reduced to wire stock. With the improved method, the cost of reducing the material to wire stock is not the only saving effected, but less power is required in order to subsequently produce the upset head or other enlargement on each blank. By virtue of the fact that a single reducing operation is required to reduce the shank to accurate final diameter in cases where the final blanks have uniform shank diameter throughout, the metal of the shanks is not unduly stressed. The improved method also enables production of blanks wherein the junction between the heads and the shanks, is not over-stressed and in which the grain of the material at this junction may be gradually deflected to create a perfect union between the adjoining portions of each blank. In forming the blanks by the improved method, the operations may be effected in one or more machines, as desired, and the heading operation may be accomplished either by single or multiple heading. In view of the fact that the extent of upsetting necessary under the improved process is materially reduced, the heading operation may ordinarily be accomplished in an effective manner by a single upset or heading blow.

A clear conception of the several steps of the improved method of forming blanks and of the manner in which the same may be performed, may be had from the accompanying description of one embodiment of the invention, the description being applied specifically to a method of forming cap screw or bolt blanks. It will be understood however that the invention is also applicable to the manufacture of other types of blanks, wherein its adoption may prove beneficial and more economical.

During exploitation of the present improved process of forming blanks, crude or previously undrawn rod stock which has been treated for the removal of scale and other undesirable coating, is severed or cut into pieces of suitable length, these pieces having the original rod stock diameter which is preferably slightly larger than that of the greatest shank diameter of the finished blank which it is desired to produce. When the finished blanks are to be provided with threads which are to extend along the entire length of the shank or unheaded portion thereof, the entire shank portion of each blank is forced through a suitable drawing die of well known form having an effective drawing diameter equal to that desired in the final blank, thus reducing the entire shank to proper and accurate diameter in a single drawing operation and producing symmetrical flow lines which are slightly curved away from the blank axis at the shank end of the head. In case the finished blanks

are to be provided with rolled threads extending along only a portion of the shank length, each blank is additionally passed through a die of well known construction having a minor effective reducing diameter equal to 70 that required for threading the blank, thus reducing the thread receiving portion of each blank to proper and accurate diameter and producing a union between the adjoining shank portions wherein the grain or flow lines are likewise symmetrical and gradually deflected. When the shank of each piece has been thus properly formed, the pieces are passed through a header wherein the heads may be formed in a well known manner. The heading and reducing operations may obviously be performed in one or a series of machines, the manner of performing the several steps being open to selection by the manufacturer. 75

From the foregoing description, it will be apparent that the present improvement enables or permits utilization of relatively crude rod stock for the production of accurately formed finished blanks having characteristics which are superior to those of the blanks produced with the method heretofore employed. The improved blanks may be manufactured at considerably lower cost, due principally to the decreased cost of the rolled rod stock as compared with that of the drawn wire stock heretofore used. The blanks produced by the improved method will obviously contain gradually distorted grain throughout their lengths, and the flow of the metal during the distorting operations will be uniform and symmetrical with respect to the blank axes, thereby producing blanks in which no portion of the metal is undesirably stressed. All of the metal of each blank is worked uniformly and the junctions between the head and shank portions are of maximum strength because of the gradual deflection of the grain at these junctions. Although the external appearance of the final product resulting from the improved method of manufacture, may not differ materially from that of the prior product, it will be evident that the physical properties of the new product are quite different and superior to those of the previous blanks. 100

It will also be apparent that the successive blanks produced by the improved method will be of accurate dimensions and of uniform and substantially identical structure. 115 The tolerance or clearance necessary in order to eliminate binding between the stock and the openings of the die, may be ignored with the improved method, as no portion of the rod stock originally employed remains undistorted in the finished blank, as in the prior methods. 120

It should be understood that it is not desired to limit the present invention to the use of any specific type of apparatus or to 130

the particular sequence in performance of the steps recited herein, for various modifications within the scope of the claims may occur to persons skilled in the art.

5 It is claimed and desired to secure by Letters Patent:—

1. The method of forming headed blanks, which comprises, severing previously un-drawn rod stock of an approximate diameter 10 transversely of its grain into pieces, directly drawing a portion of each piece longitudinally of said grain to accurate finished diameter, and directly upsetting another portion of each piece to form a head.
- 15 2. The method of forming headed blanks, which comprises, severing previously un-drawn rolled rod stock of an approximate diameter transversely of its grain into pieces, directly drawing an end of each piece longitudinally of said grain to finished diameter, and subsequently directly upsetting the opposite end of each piece to form a head.
- 20 3. The method of forming headed blanks, which comprises, severing previously un-drawn rolled rod stock of an approximate diameter transversely of its grain into pieces, drawing a portion of each piece longitudinally of said grain to a definite diameter, drawing another portion of the previously drawn 25 30 portion longitudinally of said grain to a reduced finished diameter, and upsetting another previously un-drawn portion of each piece to form a head.
4. The method of forming headed blanks, which comprises, severing elongated stock 35 of greater diameter than the finished blank shanks transversely into pieces, drawing a portion of each piece longitudinally to the largest diameter of the finished blank shank 40 while retaining the remainder of the piece at the original stock diameter, drawing a portion of said previously drawn portion to a diameter less than the largest diameter of the finished shank portion to condition said last 45 drawn portion for the rolling thereon of a thread which will merge with the adjacent end of said finished shank portion, and directly enlarging said remainder to form a head.

In testimony whereof, the signature of the 50 inventor is affixed hereto.

RICHARD M. HEAMES.
